PUNCH PRESS

William L. Allison, Phoenix, Ariz., assignor to
 Allison Steel Manufacturing Company, Phoenix, Ariz., a company of Arizona

Application September 10, 1949, Serial No. 114,999

3 Claims. (Cl. 164—104)

1

This invention relates to improvements in a punch press and more particularly provides improvements in a punch press with a continuously oscillating head.

In a punch press of the oscillating type, the head suspended above a stationary table continually moves up and down transverse to the table. A punch holder is slidably disposed in the oscillating head with a punch coupled to its lower end. The punch in this floating position lightly impinges the surface of a work piece on the table but does not pierce it. When the punch in the floating position strikes the work, the punch and holder will move upwardly with respect to the head. If the punch is to pierce the work, the holder must be locked to the head. In the prior art, this is accomplished by moving manually a locking piece or plunger into a free space above the punch holder. The punch on the next downward stroke pierces the work on the table.

An operator using the manual locking mechanism must time insertion of the plunger or locking piece with the stroke of the press. Manual operation is slow, and frequently the plunger will be engaged only partially. That is, the lower face of the plunger will cover only part of the upper end of the holder before the punch strikes the work. In consequence, there is excessive wear on holder and plunger and not infrequently, a broken part.

To remedy the shortcomings of the manually operated plunger, the plunger of my apparatus is actuated pneumatically. For that matter, the plunger may be actuated by any compressed fluid, liquid or gas. Hereinafter, the term pneumatic is used to describe all such fluid-actuated means. This pneumatically actuated plunger is much faster and hence, more certain to cover completely the top surface of the punch holder. For this reason, wear and breakage are greatly reduced. In the preferred form of my device, the operator need not remove a hand from the work piece to actuate the plunger, because a foot pedal is utilized to control an air valve that actuates the plunger. This results in a safer punch press.

Furthermore, with the use of my pneumatically actuated plunger, the number of stroke cycles per minute may be increased because the engagement of the plunger is dependent no longer upon manual operation which is necessarily slow. Hence, my invention results not only in an improved means of engagement but also in more rapid operation.

In a presently preferred form of my apparatus, 55

2

a member oscillates transversely to a table upon which the work is laid. A punch or punch holder is disposed in the member and arranged to slide transversely to the table. If the punch holder is utilized, the punch is attached to the holder's end. Means pneumatically actuated lock the punch or punch holder to the oscillating member when the punch is to pierce the work. Means are provided for releasing the punch or punch holder from the locked position after the punching operation has been completed.

These and other aspects of my invention will be understood more thoroughly in light of the following detailed description, taken in conjunction with the accompanying drawings in which:

Fig. 1 is a fragmentary front elevation of a presently preferred form of my apparatus;

Fig. 2 is a side elevation of the apparatus of Fig. 1 as viewed from the section line 2—2 of Fig. 1;

Fig. 3 is a front elevation, partly in section, taken along line 3—3 of Fig. 2 and showing the punch piercing the work; and

Fig. 4 is a top plan view along line 4—4 of Fig. 3.

As illustrated in Figs. 1 and 2, a body 12 is attached to the under surface of a cross head 13 by bolts 15, 16, the heads of which are slid into a pair of T-shaped grooves 17 in the cross head. An air cylinder housing 18 is fastened to the body parallel to the under surface of the cross head by four set screws 19. A punch holder 21 is carried in a slidable, upright position in the body. A coaxial punch 22 is fastened to the lower end of the holder by a coupling nut 23.

A table 25 below the cross head supports the work. A plate 27 is fastened to the table by a pair of bolts 28, 29, the heads of which are slid into T-shaped grooves 30 in the table. An annular bushing 33 with its bore 34 in alignment with the punch is mounted in a cylindrical recess 35 of the plate. The bore of the bushing receives the punch after it has pierced the work.

In Fig. 3, an air port 37 in the end of the air cylinder housing is connected by a hose 38 (see Fig. 1) to a source of compressed air through a foot operated valve 63. The air port opens into a horizontal bore 39. A piston 41 slidably disposed in the bore is press fitted over one end of a plunger shaft 42. The piston abuts against a vertical shoulder of a swollen section 44 of the shaft. A helical spring 46 coaxial with the shaft is placed between the other shoulder of the swollen section and a vertical face 47 of the body member.

The shaft extends horizontally from the bore into a cavity 50 of the body member. The cavity has a rectangular cross section as viewed in plan and a depth slightly greater than the thickness of a slotted plunger 52 which is slidably disposed therein. The top of the cavity is closed when the body is bolted to the cross head. A threaded end 53 of the plunger shaft screws into the right hand face 54 of the plunger (as viewed in Figs. 3 and 4).

The plunger is substantially a rectangular block with its lower face partially cut away to permit movement of the plunger over a rectangular head 56 of the punch holder which projects upwardly into the cavity. A slot 58 in the central portion of the plunger (see Fig. 4) permits the plunger to move along its path, even though the bolt 16 which fastens the body to the cross head extends vertically through the cavity and plunger.

The punch holder is cylindrical and is slidably held in a vertical bore 60 of the body by its rectangular head 56, which normally rests on the floor of the cavity. The corner 62 of the head adjoining the lower face of the plunger is rounded to provide smoother operation. Similarly the corner 62A of the plunger 52, which contacts the corner of the head, is rounded.

Whenever the punch press is in operation, the cross head and the members attached thereto will oscillate up and down above the work on the table. As long as the space above the head of the punch holder is clear (i. e. when the plunger is in its far right position as shown by dotted lines 63, 64 in Fig. 3), the punch will strike the work lightly. When the guide mark on the work is in alignment with the point of the punch, the foot operated valve is actuated by the operator and air under pressure is forced into the bore through the air port, moving the piston, shaft, and plunger to the far left (as illustrated in Fig. 3). Then the plunger occupies the former free space above the punch holder, and the punch on the next downward stroke will penetrate the work.

When the operator removes his foot from the foot valve, the air escapes and the helical spring returns the piston, shaft, and plunger to the unengaged position as indicated by the dotted lines in Fig. 3.

It is to be understood that the form of my invention, herein described and illustrated, is a preferred embodiment and that various changes may be resorted to without departing from the spirit of my invention, or scope of the claims. For example, the helical spring could be eliminated

and the plunger pneumatically actuated in both directions.

I claim:

1. In a punch press of the continuously oscillating type and including a table, a cross head oscillatable perpendicularly to the table, the combination comprising a body member affixed to the lower end of the cross head and having an elongated cavity extending transversely of the axis of oscillation and opening against the bottom face of the cross head, a bore in the bottom of said body member opening into said cavity adjacent an end thereof, a punch slidably mounted through said bore and having on its inner end an enlarged head of larger diameter than said bore, a gag slidably mounted in said cavity, the gag being shorter than said cavity but of substantially the same cross section and having a notch in the bottom thereof extending from its inner end to form an overhanging projection insertable between the bottom of said cross head and the top surface of said enlarged head to fill the space therebetween, hydraulic means for displacing said gag in the direction of said enlarged head, spring means for retracting the gag, and a foot operated valve for controlling the operation of said hydraulic means.

2. Apparatus according to claim 1 wherein the gag has a longitudinally elongated slot centrally spaced between its sides and extending through the gag from top to bottom and the body member is affixed to the cross head by a bolt passing through the said slot in the gag, the gag being free to oscillate longitudinally through a displacement defined by the longitudinal elongation of said slot.

3. Apparatus according to claim 1 wherein said enlarged head of the punch is rounded along the edge directed toward said gag and the outer lower edge of the overhanging projection of said gag is rounded, the arrangement being such that the edge of the head and the rounded edge of the gag engage as the gag is displaced towards the head.
